Primary Examiner — Karen E Eldridge Powers**(57) CLAIM**

The ornamental design for a ponytail accessible railroad hat, as shown and described.

DESCRIPTION

FIG. 1 is a side elevation view of a ponytail accessible railroad hat showing my new design;

FIG. 2 is a back elevation view thereof;

FIG. 3 is a front elevation view thereof;

FIG. 4 is a top plan view thereof;

FIG. 5 is a bottom plan view thereof;

FIG. 6 is a front perspective view thereof; and,

FIG. 7 is back perspective view thereof.

1 Claim, 6 Drawing Sheets---
